UNITED STATES PATENT OFFICE.

KARL EIERMANN, OF MUNICH, GERMANY, ASSIGNOR TO THE FIRM GEBR. BAUMANN, MASCHINEN UND MOTORFABRIK G. M. B. H. & CIE., COMMANDITGESELLSCHAFT, OF MUNICH, GERMANY.

INTERNAL-COMBUSTION ENGINE.

Application filed August 7, 1926, Serial No. 127,926, and in Germany November 13, 1924.

This invention relates to internal combustion engines of the injection type and its main objects are the provision of means whereby an increased output of the engine 5 combined with utmost economy of fuel may be obtained.

A further object is to provide an improved manner of distribution of the injected fuel in the combustion chamber and 10 effecting a thorough mixture of the fuel with the air in the cylinder, as well as a reduction of the heat losses in the gaseous mixture during its first phase of expansion after ignition.

15 Other objects are the elimination of undesirable pressure increases during the process of combustion, and the injection of the fuel under comparatively low pump pressures such as are usual in engines having a 20 so-called ignition chamber to serve as a preliminary combustion chamber.

With these and other objects in view, the invention mainly consists in the provision of an engine of the said type in which the 25 principles of an ignition chamber engine and of a direct injection engine are so combined as to fully secure the advantages of both these types without, however, incurring their disadvantages.

30 To this end the engine according to the invention is provided with a distributor embodying a perforated closed hollow body of substantially globular form or with inside walls in contour conforming substantially 35 to the shape of a jet of fuel injected thereto, while its outside wall corresponds in shape substantially to a semi-spherical cavity formed in the top of the piston, the arrangement being such that any large cooling surfaces are eliminated during the first 40 phase of expansion, and that, on the other hand, scorching of the distributor is prevented by its metallic connection with the water-cooled cylinder head.

45 The accompanying drawing illustrates the invention by way of example. Fig. 1 shows a central longitudinal section through the top portion of an engine cylinder in a more diagrammatic manner, and Fig. 2 is a cross 50 sectional view through a modified form of distributor.

The piston of the engine is denoted by the letter *a*, the water-cooled cylinder cover by the letter *b*, and the injection valve by *c*. 55 The distributor *d*, having orifices or perfora-

tions *e* in its walls, is screwed or otherwise secured into the cylinder cover and in this way is in heat conducting connection with the water-cooled parts of the engine cylinder. For the purpose of obtaining a proper starting of the ignition process and an unobstructed passage of the gases from the distributor into the combustion chamber, the distributor body *d* is shown in a globular form having its inner wall pear-shaped or 60 conforming substantially to the shape of a jet of fuel nozzleled or entering thereinto from the injection valve, while its outside wall is made to correspond in shape substantially to a semi-spherical cavity *f* in the 65 piston which substantially encompasses the lower end of the distributor body in the upper dead center position of the piston and serves as a preliminary combustion chamber within which the first combustion and 70 expansion phases are caused to take place. The illustrated arrangement of the distributor *d* concentrically within said cavity (when the piston is in its upper dead centre 75 position), and of the large number of orifices or small perforations *e* in the distributor, ensures the distribution of the fuel in such manner that the small individual jets of the fuel emanating from said perforations will impinge only upon the walls of 80 the semi-spherical cavity in the piston. As these walls are entirely uncooled, no losses of heat due to cooling influences of cylinder walls are incurred and it is evident that by 85 this manner of fuel distribution, which proceeds comparatively slow in relation to the traveling speed of the piston, a practically constant pressure during the combustion stroke is obtained and the occurrence of injurious pressure increases, successfully prevented.

Owing to the fact that the outer wall of the distributor *d* conforms substantially to the shape of the combustion chamber or cavity in the piston, and due to the disposition or arrangement of the small perforations *e* therein, the fuel, which is ejected under high pressure through said perforations, penetrates the highly compressed air in the combustion chamber in a finely divided state and thus ensures complete combustion. If a higher degree of turbulence is desired, the perforations *e* may be drilled tangentially through the wall of the distributor as shown at *g* in Fig. 2, in order to 100 105 110

2
impart a spiral motion to the gases emanating therefrom.

The distributor δ which is preferably made of a good heat-resisting material, also acts as a hot bulb and thus forms an auxiliary ignition member, within which the amount of heat required for proper ignition and complete combustion is concentrated. This point of heat concentration, located in the centre of the semi-spherical combustion chamber, ensures a good working of the engine and a full utilization of the injected fuel, while scorching is prevented owing to the metallic connection of the distributor with the water-cooled portions of the cylinder cover, into which the said distributor is screwed or otherwise secured.

What I claim is:—

1. In an internal combustion engine working on the injection principle, a piston adapted to reciprocate in the engine cylinder and having a semi-spherical combustion chamber formed in its head, a fuel injection valve and a substantially pear-shaped perforated ignition chamber into which said valve injects fuel, the outer wall of said ignition chamber being of a shape conforming substantially to the shape of the combustion chamber in the piston head and serving to distribute the fuel or burning gases emanating from the interior thereof evenly over or within the combustion chamber.

2. In an internal combustion engine working on the injection principle and having a water-cooled working cylinder, a piston adapted to reciprocate in said cylinder and having an uncooled substantially semi-spherical cavity in the head thereof providing a combustion chamber for fuel, a fuel injection valve, a fuel distributor into which fuel is injected through said valve, comprising a perforated globular-shaped chamber secured to the cylinder head in position to project into the combustion chamber in the piston head concentrically therewith and through which the injected fuel discharges into the combustion chamber, the inner wall of said distributor being pear-shaped to conform substantially to the shape of a jet of fuel from the injection valve and the outer wall thereof being of a shape conforming substantially to the shape of said semi-spherical cavity in the piston.

3. In an internal combustion engine working on the injection principle and having a water-cooled working cylinder, a piston adapted to reciprocate in said cylinder and having an uncooled substantially semi-spherical cavity providing a combustion chamber

in its head, a fuel injection valve, a fuel distributor secured to the cylinder head in position to project into said cavity in the piston head and into which fuel is injected through said valve, said distributor being of hollow globular form having an inner wall of pear-shape conforming substantially to a jet of fuel injected thereinto and an outer wall conforming substantially with the shape of the semi-spherical cavity in the piston and provided with perforations for discharging fuel or burnt gases therefrom, the radial distance of all points on the outer surface of the distributor to the wall of the semi-spherical cavity in the piston being the same.

4. In an internal combustion engine working on the injection principle and having a water-cooled working cylinder, a piston having an uncooled substantially semi-spherical cavity formed in its head serving as a combustion chamber, a fuel injection valve, a fuel distributor secured to the cylinder head in position to project concentrically into said cavity in the piston head when the piston is in its upper dead center position and into which fuel is injected through said valve, said distributor being of hollow globular form having an inner wall shaped to conform substantially to a jet of fuel injecting thereinto and an outer wall conforming substantially with the shape of the semi-spherical cavity in the piston and provided with tangentially disposed perforations for discharging fuel or burnt gases therefrom with a spiral-like motion into the combustion chamber.

5. In an internal combustion engine adapted to work on the injection principle, a reciprocating piston having a substantially semi-spherical cavity in the head thereof serving as a combustion chamber within the cylinder, a fuel injection valve and a globular-shaped perforated ignition chamber and distributor into which fuel is initially injected through said valve, said chamber having its inner wall of pear-shape conforming substantially to the shape of a jet of the fuel injected thereinto and its outer wall conforming substantially to the shape of said cavity in the piston head by which the lower end of the chamber is substantially encompassed and into which the latter is adapted to project and distribute fuel concentrically thereof when the piston is in its upper dead center position.

In testimony whereof I affix my signature.

KARL EIERMANN.
